Primary Examiner — Antoine D Davis*(74) Attorney, Agent, or Firm* — Harness, Dickey & Pierce, P.L.C.**(57) CLAIM**

The ornamental design for a thermostat, as shown and described.

DESCRIPTION

FIG. 1 is a perspective view of the thermostat; and, FIG. 2 is a front elevation view thereof.

The views of the thermostat not shown form no part of the claimed design. The features shown in broken lines depict environmental subject matter only and form no part of the claimed design.
